UNITED STATES PATENT OFFICE.

JOSEPH MERLE, OF BENSONHURST, NEW YORK.

LIQUID-FUEL BURNER.

1,271,923.

Specification of Letters Patent. Patented July 9, 1918.

Application filed May 25, 1917. Serial No. 170,804.

To all whom it may concern:

Be it known that I, JOSEPH MERLE, a citizen of the French Republic, residing at Bensonhurst, in the county of Kings and 5 State of New York, have invented certain new and useful Improvements in Liquid-Fuel Burners, of which the following is a full, clear, and exact description, such as will enable other skilled in the art to which 10 it appertains to make and use the same.

This invention relates to liquid fuel burners, and with regard to its more specific features, a liquid fuel burner having means for vaporizing the fuel and for consuming the 15 fuel in the form of a vapor.

An object of this invention is to provide a device of the character described in which the combustion orifice will be maintained free from obstruction so as to insure a clean 20 flame.

Another object of this invention is to improve the vaporization of the fuel by preventing the accumulation of products of combustion in the vaporizing chamber.

25 Another object of the invention is to provide a device of the character described in which the height of the flame may be controlled by throttling the vapor passages.

Other objects will be in part obvious and 30 in part pointed out hereinafter.

The invention accordingly consists in the features of construction, combinations of elements and arrangement of parts which will be exemplified in the construction hereinafter set forth, and the scope of the application of which will be indicated in the 35 following claims.

In the accompanying drawings forming part of the specification in which similar 40 reference characters refer to similar parts throughout the several views,

Figure 1 shows an elevation of a burner made in accordance with this invention, certain of the parts being in sections more 45 clearly to illustrate the invention.

Fig. 2 is a sectional view along the line II—II of Fig. 1.

Fig. 3 is a view similar to Fig. 1 of a modified form showing the parts in relation 50 to close the valves.

Fig. 4 shows the modification illustrated in Fig. 3 in a section taken at the valves showing the valves open.

Fig. 5 is a view similar to Fig. 3 of a modification. 55

Fig. 6 is a view similar to Fig. 2 of another modification.

The numeral 1 indicates a rod adapted as at 2 to be connected to a suitable container 3 for a liquid fuel. 60

A block 4 is mounted for longitudinal movement on this rod 1 which may conveniently be done by providing screw thread 5 upon the rod adapted to mate with corresponding threads upon the block. Mounted upon block 4 in position to surround the outer end of the rod 1 is a vaporizing chamber 6 provided at its outer end with a combustion orifice 7, which is preferably situated so as to be coaxial with the screw 70 thread 5 and with the rod 1. On the interior of the vaporizing chamber 6 between the walls of that chamber and the rod 1, there is provided some means for increasing the heating area of the vaporizing chamber. 75 As illustrated in Fig. 1 this comprises a cylindrical sheet of wire cloth 8.

In order to control the flame means are provided whereby a relative movement between the vaporizing chamber 6 and the rod 80 will cut off communication between the vaporizing chamber 6 and the combustion orifice. As illustrated, the upper portion as 9 of the rod has a conical end as shown at 10, and the combustion chamber is provided 85 with a complementary seat 10^a adapted to coöperate with end 10 to form a valve 11.

For the purpose of maintaining the combustion orifice 7 free from obstruction, there may be provided upon the outer end of the 90 rod 1 coaxial with the combustion orifice 7 a cleaning pin 12, so arranged that when the valve 11 is closed, the pin 12 will project through the combustion orifice and thrust out any dirt or combustion products that 95 may be lodged therein. When the valve 11 has been opened to permit the passage of vapor from the vaporizing chamber through the combustion orifice, the pin 12 will be withdrawn from the orifice. 100

For the purpose of facilitating the turning of the block 4 on the screw thread 5 to regulate the flame, a handle 15 may be provided, connected to the block 4; and for the purpose of facilitating the starting of the burner by initially heating the vaporizing vapor, there may be provided an annular pan 16 surrounding the base of the vaporizing chamber in which a suitable fuel may be placed, the burning of which will heat the vaporizing chamber.

For the purpose of conducting the fuel from the interior of the container 3 to the interior of the vaporizing chamber 6, a suitable conduit 18 is provided which may conveniently comprise an opening through the rod 1 from the bottom upwardly to a point opposite the vaporizing chamber, which may open laterally into the vaporizing chamber 20 as shown at 19.

In Figs. 3, 4 and 5 are illustrated modifications in which means are provided for closing communication between the fuel supply and the vaporizing chamber as well as the vaporizing chamber and the combustion orifice.

The valve construction of Figs. 3 and 4 is as follows: The parts 1^a and 9^a are made separate, the part 1^a is provided at its upper end with a valve seat 20 with which the lower end of the rod 9^a is adapted to co-operate to form a valve 21. In order to retain the valve 21 normally open, a spring 22 may be provided bearing at one end against the rod 1^a, and at the other end against a shoulder 23 upon the rod 9^a.

In the modification shown in Figs. 3 and 4 the vaporizing element is of a different type from that shown in Fig. 1, and comprises a hollow cylinder 8^a, the outer surface area of which may be increased as by having a helical groove cut therein. This cylindrical member 8^a will be provided with a central bore for the rod 9^a, which at some point will be increased in diameter to provide a shoulder 24 adapted to co-operate with a shoulder 25 upon the rod 9^a to limit the movement of the rod 9^a responsive to the spring 22.

In Fig. 5 is illustrated a modification involving the same valve construction as in Figs. 3 and 4 used with the vaporizing element as illustrated in Fig. 1. In this modification, for the purpose of guiding the rod 9^a and retaining the same in position to co-operate with the valve seat 20 and the combustion orifice 7, a cylindrical tube as 240 may be provided which is conveniently screwed to the upper end of the rod 1. This tube 240 will be provided with a shoulder 24^a for co-operation with a shoulder 25^a upon the rod 9^a to limit the movement of the part 9^a responsive to the spring 22.

In the modification illustrated in Fig. 6,

a third form of vaporizing element is illustrated comprising a cylinder of metal with its outer surface polygonal in cross section.

In each of the various modifications of this invention the vaporizing element will preferably be held against rotation on the rod 1 whereby a relative motion between the vaporizing chamber and the element will be produced by the adjustment of the flame, and the shape and size of the vaporizing element will be such that while at all times affording passage for the vapor through the vaporizing chamber, yet the relative movement between the element and the vaporizing chamber may be utilized to keep the vaporizing chamber free from deposits or dirt. As illustrated, the vaporizing element 8 in the form illustrated in Figs. 1 and 5 may be provided with a support 28 surrounding the rod 1. In this form the support 28 and in the form illustrated in Figs. 3, 4 and 6 the vaporizing element itself may be provided with a non-cylindrical portion, as, for example, a square recess 29 adapted to co-operate with a non-cylindrical portion as for example, a square shoulder 30 on the rod 9, whereby the vaporizing element may move longitudinally upon the rod 1 but cannot rotate thereon. By this construction the vaporizing element moves circumferentially on the interior of the vaporizing chamber whenever the height of a flame is adjusted, whereby the interior of the combustion chamber is freed from carbon deposits and other impurities which may interfere with the transfer of heat from the walls of the combustion chamber to the fuel on the interior thereof, and might obstruct the fuel passages.

The operation of this device is as follows: The orifice 18 having been placed in communication with the fuel supply and sufficient pressure having been placed upon the fuel to force it out through the lateral orifice 19 into the vaporizing chamber 6, the heat of the chamber 6 will cause the vaporization of the fuel, and if the communication between the vaporizing chamber and the combustion orifice 7 be opened, the vapor discharged through the orifice 7 may be ignited. Should it be desired to reduce the flame, the handle 15 may be turned to lower the combustion chamber 6 upon the rod 9 and thereby cause the conical end 10 of the rod 9 to throttle the vapor as it passes to the combustion orifice 7. This will cause a reduction from the quantity of gas into the orifice 7, thereby reducing the flame. At the same time increased pressure in the chamber 6 will cause a reduction in the quantity of fuel delivered to the chamber 6 from the fuel reservoir 3, and the lower flame will cause a lowering of the temperature of the combustion chamber 6, whereby

the quantity of vapor generated in the vaporizing chamber will be reduced. Should it be desired to shut off the supply of fuel by turning the handle 15 still more, the 5 conical end 10 may be caused to completely close the passage of the chamber 6 to the combustion orifice and thus completely shut off the supply of fuel.

- In the modification shown in Fig. 3, after 10 the passage of vapor from the vaporizing chamber 6 to the combustion orifice 7 has been closed by movement of the handle 15, a still further turning of the handle will cause the communication between the fuel 15 reservoir 3 and the vaporizing chamber 6 to be completely closed by means of the coöperating elements 20 and 21, whereby if the packing between the block 4 and the thread 5 should be slightly loose, the pressure in 20 the tank 3 will not be permitted to escape, even though the packing between the block 4 and the screw 5 should be slightly loose.

The frequent movement of the vaporizing element in the vaporizing chamber of 25 the pin 12 in the combustion orifice 7 will keep the fuel passages free from dirt and obstruction without danger of damaging them by unskillful attempts to clean them out. Thus the satisfactory operation of the 30 burner is maintained.

Thus by the above construction is accomplished among others, the objects hereinbefore set forth.

Having described my invention, what I 35 claim as new and desire to secure by Letters Patent is:

1. A liquid fuel burner comprising, in combination, a vaporizing chamber provided with an orifice, a member relative to 40 which said chamber is movable for conducting fuel to said chamber, said member being provided with means for increasing the evaporation surface in the vaporizing chamber and with means operative by said relative movement to close said orifice.

2. A liquid fuel burner comprising, in combination, a vaporizing chamber provided with an orifice, a member relative to 50 which said chamber is movable for conducting fuel to said chamber, said member being provided with means for increasing the evaporation surface in the vaporizing chamber and with means operative by said relative movement to close said orifice, said 55 means for increasing the evaporation area being adapted to bear against the inner surface of the vaporizing chamber whereby said chamber is freed from carbon deposit by the relative movement between said member and the vaporizing chamber.

3. A liquid fuel burner comprising, in combination, a vaporizing chamber provided with an outlet, a member relative to 60 which said chamber is movable, for con-

ducting fuel to said chamber, said member being provided with metallic edges adapted to be operated by the relative movement to free the inner surface of the chamber of carbon, said member being adapted to increase the evaporative surface in the combustion chamber and being provided with means operative by said relative movement for closing said orifice.

4. A liquid fuel burner comprising, in combination, a rotatively mounted vaporizing chamber adapted to receive fuel from a supply and having an orifice, and a valve member relative to which said chamber is longitudinally movable upon rotation of said chamber, adapted by said relative movement to close said orifice and subsequently shut off fuel from said supply.

5. A liquid fuel burner comprising, in combination, a vaporizing chamber having an inlet for liquid fuel and outlet for vaporized fuel, a member adapted to close both inlet and outlet, and means for preventing the closing of the inlet until the outlet has been closed.

6. A liquid fuel burner comprising, in combination, a vaporizing chamber having an outlet for vaporized fuel, a member adapted to conduct liquid fuel to said chamber and relative to which said chamber is movable, said member being provided with a guideway, and a rod movable in said guideway and adapted to be caused by said relative movement to close said outlet and to shut off the supply of liquid fuel to said chamber.

7. A liquid fuel burner comprising, in combination, a vaporizing chamber having an outlet for vaporized fuel, a member adapted to conduct liquid fuel to said chamber and relative to which said chamber is movable, said member being provided with a guideway, a rod movable in said guideway and adapted to be caused by said relative movement to close said outlet and to shut off the supply of liquid fuel to said chamber, and means causing said rod to close said outlet before shutting off the supply of fuel to said chamber.

8. A liquid fuel burner comprising, in combination, a member having a bore adapted to communicate with a supply of fuel under pressure, a vaporizing chamber communicating with the bore of said member, said vaporizing chamber being provided with a combustion orifice, a part adapted to throttle the communication between the vaporizing chamber and said orifice and between said member and said vaporizing chamber, and means for holding the communication between said member and said vaporizing chamber open until the communication between said chamber and said orifice has been closed.

9. A liquid fuel burner comprising, in combination, a member having a bore adapted to conduct fuel from a supply of fuel under pressure, a vaporizing chamber 15
5. communicating with said bore and provided with a combustion orifice and an inlet orifice, the vaporizing chamber being movable relative to said member, a rod having means at one end to shut off the supply of fuel to
10 the vaporizing chamber, and having at the other end means to close communication between the vaporizing chamber and the combustion orifice, means normally urging said rod away from the inlet orifice of said combustion chamber, whereby the inlet orifice is normally maintained open, and means to limit the movement of said rod responsive to said urging means.

In testimony whereof I affix my signature, in the presence of two witnesses.

JOSEPH MERLE.
